US0D1007244S

(12) **United States Design Patent** (10) **Patent No.:** **US D1,007,244 S**
(45) **Date of Patent:** **** Dec. 12, 2023**

(54) **FOOD STORAGE CONTAINER**

(71) Applicant: **DONGGUAN OUMENG
HOUSEWARE PRODUCTS CO.,
LTD**, Dongguan (CN)

(72) Inventor: **Jingsheng Xu**, Yueyang (CN)

(73) Assignee: **DONGGUAN OUMENG
HOUSEWARE PRODUCTS CO.,
LTD**, Dongguan (CN)

(**) Term: **15 Years**

(21) Appl. No.: **29/897,052**

(22) Filed: **Jul. 11, 2023**

(51) LOC (14) Cl. **07-01**

(52) U.S. Cl. **D7/510; D9/432**

(57) **CLAIM**

The ornamental design for a food storage container, as shown and described.

DESCRIPTION

FIG. 1 is a perspective view of a food storage container showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the food storage container.

The broken lines in FIG. 9 depict portion of the food storage container that form no part of the claimed design.

1 Claim, 9 Drawing Sheets
